Primary Examiner — John Windmuller*Assistant Examiner* — John R Yeh(74) *Attorney, Agent, or Firm* — Phillip Black; James P. Dossey**CLAIM**

The ornamental design for a cross-shaped safety switch, as shown and described.

DESCRIPTION

FIG. 1 is an isometric front, left side view showing my design for a cross-shaped safety switch;

FIG. 2 is a front view thereof;

FIG. 3 is a top view thereof;

FIG. 4 is a left side view thereof;

FIG. 5 is a rear view thereof;

FIG. 6 is an isometric rear, right side view thereof; and, FIG. 7 is a front view as installed on a lower receiver component of a typical rifle.

The broken away lines in FIG. 7 depict environmental subject matter and form no part of the claimed design.

The broken lines in the drawings represent environment of the cross-shaped safety switch and form no part of the claimed design.
